Design of a Wardrobe
and Cupboard for a
Bath Room
in the style of
the year 1843

Jordan S. Mott, City of New York
Letters Patent No. 7, dated August 17th 1843

The Schedule referred to in these Letters Patent and making
part of the same. -

To all whom it may Concern: Be it known that
I, Jordan S. Mott, of the City of New York, in the State
of New York, have designed and invented a new and ori-
ginal shape or configuration of a Bathing Tub, to be
made of cast iron, the whole of the body of said Tub being
cast in one single piece of metal, and I do hereby declare
that the accompanying drawing affords a clear and exact
view of the shape and configuration of my said Tub, -
which tub I vary in size, having already made three bat-
htubs thereof, but in each case I preserve the same shape
or configuration.

Fig. 1 represents a top view of my Tub. Fig. 2. a vertical section through along its centre, from end to end. Fig. 3 is a vertical cross section in the line a, a. of fig. 1; and fig. 4 a similar section in the line b, b.

The feet c, c, may be cast in one piece with the tub, or they may be fitted into dovetail grooves, as is commonly done with the feet of stoves.

I sometimes provide a recess in the foot of the tub, to receive a Thermometer, the tube of which may be guarded from accident by means of a wire garter, or other device. In fig. 1, d, represents the place of such Thermometer, which is contained in the curved recess c, c; in all other respects, the shape and configuration of my Tub is to remain unchanged. I have represented the rim E, E, of my tub as curved, but it will be manifest that this part may be made flat, without changing the general form and configuration in any essential or substantial particular, and that a tub may be readily cast from any pattern and the form of the rim be altered by the moulder, in the flask; and as one main object in obtaining a patent for the shape and configuration of such an article is to prevent the piracy of patterns, it will be manifest that such piracy might be as actually committed where there was a change of form in the rim, as where it was made in that herein represented, and that the so doing would be a violation of my rights.

Having thus, fully described, by references to the accompanying drawing, the shape and configuration of my last-named Bathing tub, What I claim as constituting my invention or design therein, is the, forming of the respective parts of the body thereof with
